UNITED STATES PATENT OFFICE.

JOHN HARKNESS, OF AYR, SCOTLAND.

BUILDING STRUCTURE.

1,350,019.

Specification of Letters Patent. Patented Aug. 17, 1920.

Application filed July 15, 1919. Serial No. 310,964.

To all whom it may concern:

Be it known that I, JOHN HARKNESS, a subject of the King of the United Kingdom of Great Britain and Ireland, and residing at Ayr, Scotland, have invented a certain new and useful Improvement in Building Structure, of which the following is a specification.

This invention relates to an improvement in wall construction.

The invention consists broadly in a wall structure comprising upright concrete beams or slabs of H-section set on a cast base with the edges of the flanges abutting and having a tongue and groove or similar interlocking means with one another, the webs of said upright beams constituting studs, a horizontally disposed concrete beam of substantially H-section having a tongue and groove or the like interfitting with the upper ends of the upright beams and presenting a channel along the upper portion of the H and a channel along the lower portion of the H, the upper channel serving to accommodate concrete or reinforced concrete, and the lower channel being engaged by the studs.

The invention is illustrated in the accompanying drawing in which Figure 1 is an elevation of a wall construction, Fig. 2 a plan, Fig. 3 a vertical section, Fig. 4 an isometric projection and Fig. 5 a fragmentary view showing the horizontal beam in position.

As shown, the wall is formed of upright beams or slabs 1 of concrete of H section set on a suitably cast base 2, the flanges forming the inner and outer faces of the wall, the edges of the flanges of adjoining beams having a tongue and groove fitting with one another, as indicated at 3, the webs of said upright beams constituting studs 4 the upper ends of which protrude from the beams and the lower ends of which stop short of the lower ends of the beams by an amount equal to the depth of the foundation fillet.

The upright beams of each wall have a tongue and groove or other fitting at their upper ends as indicated at 5 with a horizontally disposed concrete beam 6 of substantially H section forming a lintel course, of which the channel 7 forming the upper portion of the H is filled with concrete in which may be embedded reinforcement, while the

studs 4 fit into the channel 8 forming the lower portion of the H.

The upright flanges of the beam 6 may be thickened below the web to accommodate reinforcing rods or the like (not shown).

The web of the beam 6 need not be located midway of the flanges as shown, it being necessary only to provide a lower channel large enough to accommodate the studs 4.

As shown in Figs. 1 and 2, certain of the upright beams 1 may stop short of the level of the horizontal beam 6, so as to leave space for a window frame or frames, such as 9.

Air-holes 10 may be formed in the upright beams 1 to connect the cavities formed in the wall between the flanges of the upright beams.

At external and internal angles, the corner upright beams may be formed as shown in Fig. 2. The cavities at the corners may be filled with concrete to constitute pillars.

I claim:

1. A wall structure, comprising a base, upright beams of H section set on said base with the edges of the flanges abutting and interengaged with each other, said beams forming integral connected outer and inner faces of a cavity wall, the webs of said beams constituting studs and protruding at the upper edges beyond the flanges, and a horizontally disposed beam of substantially H section and of a cross section equal to that of said upright beams and fitting the upper ends of the said upright beams.

2. A wall structure comprising a base, upright concrete beams of H section set on said base with the edges of the flanges abutting and interengaged with one another, said beams forming vertically connected outer and inner faces of a cavity wall, and the webs of said beams constituting studs protruding at the outer edge beyond the flanges, and a horizontally disposed concrete beam of substantially H section and of a cross section equal to that of said upright beams, the flanges of which horizontally disposed beam abut the flanges of said upright beams.

In testimony whereof I have signed my name to this specification in the presence of two subscribing witnesses.

JOHN HARKNESS.

Witnesses:

KATE FOTHERINGHAM,
ISABEL ROLLO.
